(57) **CLAIM**

The ornamental design for a coin sorter housing, as shown and described.

DESCRIPTION

FIG. 1 is a perspective view of a coin sorter housing showing our new design, together with a door which can be selectively mounted thereon;

FIG. 2 is a perspective view thereof without the door;

FIG. 3 is a front elevational view thereof;

FIG. 4 is a right side elevational view thereof, the left side elevational view being a mirror image thereof;

FIG. 5 is a rear elevational view thereof;

FIG. 6 is a top plan view thereof; and,

FIG. 7 is a bottom plan view thereof.

The parts shown in broken lines in FIG. 1 are shown for illustrative purposes only and form no part of the claimed design.
